UNITED STATES PATENT OFFICE

CLYDE SWIGERT, OF ST. JOSEPH, MICHIGAN, ASSIGNOR, BY MESNE ASSIGNMENTS, TO
ST. JOSEPH IRON WORKS, OF ST. JOSEPH, MICHIGAN, A CORPORATION OF MICHIGAN

ART OF MAKING BASKETS OR OTHER RECEPTACLES

Original application filed September 16, 1925, Serial No. 56,560. Divided and this application filed
September 1, 1927. Serial No. 216,834.

My invention relates to baskets or other receptacles wherein the annular wall is composed of a plurality of panels or staves, and has reference more particularly to the method whereby the panels or staves are first connected in series to form an elongated mat which is then shaped into receptacle form and provided with a bottom and hoops, this present application being a division of my application Serial No. 56,560, filed September 16, 1925.

The principal objects of my invention are to provide an improved method for making a basket or similar receptacle; to construct the annular wall of the receptacle in an improved manner; to unite the panels or staves of the annular wall in the form of an elongated mat preparatory to the making of the basket or receptacle; to utilize a strip, which subsequently forms a hoop, as the means for connecting the staves in the preliminary form; to connect the staves in a manner whereby they are capable of fanning out to form a tapered receptacle; to attach the hoops and bottom to the mat as the latter is shaped in receptacle form so that the construction of the receptacle is accomplished as the wall is shaped; and in general to provide a simple, convenient and effective method for making a basket or other receptacle wherein the annular wall is composed of a number of upright panels.

On the drawings:

Fig. 1 is a top view of a machine which may be used for making a basket in accordance with my invention;

Fig. 2 is a fragmentary and end view of the form of said machine, showing a stapling device thereover and the mat support and a hoop guide in section;

Fig. 3 is a fragmentary side view of the form and stapling devices showing the mat support in section;

Fig. 4 is a perspective view, partly broken

away, of a mat which is used in making a basket in accordance with my invention;

Fig. 5 is a perspective view of the basket bottom; and

Fig. 6 is a perspective view of the completed basket with portions broken away to disclose details.

The basket or receptacle which my present invention is designed to make is shown in Fig. 6 and comprises an annular tapered wall composed of upright panels 1, which are preferably overlapped and have their upper ends secured by staples or other suitable fasteners 2 between inner and outer hoops 3 and 4. A bottom indicated as a whole at 5 and comprising a hoop 6 having a plurality of crossed slats 7 secured to the edge thereof, or other form of bottom with annular flange corresponding to the hoop 6, is located in the lower end of the basket, and the lower ends of the panels 1 are secured by suitable fasteners 8 between the bottom hoop 6 and the outer hoop 9. An intermediate hoop 10 is preferably provided on the outside of the basket between the upper and lower ends of the panels 1 and secured to the latter by fasteners 11.

In making this basket in accordance with my present invention, the staves 1 are first arranged in series, either edge to edge or with their edges overlapping as shown in Fig. 4, and these staves are secured together in a suitable manner so that they can be fed into the basket making machine as a unitary structure or mat and so that they will fan out to give the walls of the basket a tapered form. In practice I prefer to connect the panels 1 by means of a strip 12 which subsequently becomes the outer hoop 9 at the bottom of the basket, said strip 12 being laid over the lower ends of the panels 1 and secured thereto by fasteners 13. When the panels have their edges overlapped as shown herein, these fasteners are preferably inserted through the overlapped portions as this

holds the panels more securely against displacement as each panel is thereby fastened at two points and at the same time permits the necessary fanning out of the panels. The 5 strip 12 extends only part way over the first panel 1 (that is the one indicated at the right hand end of Fig. 4) while this strip 12 projects beyond the last panel 1 (which is the panel at the left hand end of Fig. 4) so that 10 the latter panel may overlap the first mentioned panel when the mat is shaped in an annular form and so that the projecting end of the strip 12 will overlap the other end of said strip and permit the two ends to be 15 staled together.

For shaping the mat of Fig. 4 and completing the basket, a machine such as shown herein may be used, comprising disks 14, 15, 16 and 17, of which the disks 14, 15 and 16 20 are secured on a shaft 18, which is carried by a bearing 19 of a standard 20 and provided with a ratchet wheel 21, which is advanced in a step by step manner by a pawl 22, the extent of each intermittent movement being 25 regulated in accordance with the width of the panels 1, so that the fasteners which are applied in the construction of the basket are located in substantially the same relative position with respect to each panel, preferably 30 through the overlapped portions of said panels. This machine has a plurality of staplers 22, 23 and 24, arranged respectively above the disks 14, 15 and 17, so as to cooperate with these disks in applying the staples.

The disk 17 is relatively movable with respect to the disks 16, being pivoted on the upper end of an arm 28, which said arm is mounted in any suitable manner on the frame of the machine, so that it may be moved to 40 and from the disk 16. This disk 17 supports the basket bottom in the operation of making the basket and clamps the panels 7 between the disks 16 and 17 with the hoop 6 of the bottom extending over the edge of the disk 17, as shown in Fig. 3.

The disk 14 is designed to support the inside upper hoop 3 of the basket in the operation of making the latter and is preferably formed with a reduced portion 26 with a 50 bevel 27 therebetween to facilitate the applying of the hoop 3 on the disk 14. The disk 15 does not have any hoop mounted thereon, but serves merely as a form and as an anvil for the stapling device 23. Said disk is preferably formed with a beveled edge 55 28 for facilitating the removal of the completed basket from the form.

Mounted at one side of the top of the form or disks 14, 15, 16 and 17, and extending laterally therefrom is a support or feed table 60 29 carried by a standard 30. This feed table 29 has an upturned flange 31 along one edge for engagement with the free ends of the panels 1 in guiding the mat of Fig. 4 onto 65 the form or disks 14, 15, 16 and 17. At the

other edge of the feed table 29 are a number of apertured ears 32 for bolts 33, which engage in slots 34 of ears on a plate 35, which is channelled on the under side or otherwise suitably formed to fit the band 12 and insure proper feeding of the mat onto the form. In view of the slots 34, this guide 35 is adjustable so that the mat for forming the annular wall of the basket may be fed onto the form at the proper place.

Hoop guides 36 and 37 are arranged respectively adjacent the stapling devices 22 and 23 for guiding strips of material 38 and 39 respectively onto the exterior surface of the annular shell as it is being formed, so that the strips are secured by the stapling devices 22 and 23 to the annular shell and form the hoops 4 and 10 respectively.

Assuming now that a mat such as shown in Fig. 4 had been formed, this mat is placed on the support or feed table 29 with the band 12 engaged in the channel on the under side of the guide 35 and with the edges at the free ends of the panels 1 adjacent the upturned flange 31. A hoop 3 is placed on the disk 14, and a bottom 5 is clamped between the disks 16 and 17 with the hoop 6 extending over the edge of the disk 17. Hoop stock or strips 38 and 39 are then started in the guides 36 and 37 respectively. The foremost panel 1 of the mat is then brought under the stapling devices 22, 23 and 24 and the ends of the strips 38 and 39 fed down under the staplers 22 and 23. The machine is then started in operation, and the first operation of the stapling devices secures the ends of the strips 38 and 39 to the foremost panel 1, at the same time fastening the upper end of this first panel between the end of the band 38 and the hoop 3, and the stapling device 24 also fastens the end of the strip 12 and the foremost panel 1 to the hoop 6.

The mat is now connected with the hoops 3 and 6, which rotate in a step by step manner with the form, and the bands 38 and 39 are also connected with the leading panel 1. By reason of this connection, as the form, consisting of the disks 14, 15, 16 and 17, is advanced in a step by step manner by the pawl 22 and ratchet wheel 21, the mat of Fig. 4 and the bands 38 and 39 are fed onto the form in a step by step manner, and at each interval of rest the stapling devices 22, 23 and 24 apply a series of staples 2, 11 and 8 respectively.

In view of the gradually diminished size of the disks 14, 15, 16 and 17, a tapered form results, and as the mat is fed onto this form the panels or staves 1 are fanned out so as to give the completed basket or receptacle a tapered form corresponding to the form on which the basket is made.

It will be readily understood that it is not necessary to form the mat as shown in Fig. 4, as said figure merely illustrates one of the

many ways in which the mat may be constructed. The strip of material for connecting the slats or panels may be at the upper edge and arranged to form either the inner or outer hoops 3 or 4, or it may be arranged midway between the ends of the panels so as to form the hoop 10. Moreover the strip, such as 12, may be entirely omitted and the overlapping portions of the panels merely 10 stapled together to form the mat and insure that each successive panel will follow the preceding panel as the latter is stapled on the form and advanced by the latter.

While I have shown and described my invention in a preferred form, I am aware that various changes and modifications may be made without departing from the principles of my invention, the scope of which is to be determined by the appended claims.

20 I claim as my invention:

1. The method of making a receptacle which comprises connecting a plurality of panels in substantially parallel relation so as to form an elongated mat having portions 25 of the panels capable of being deflected laterally of the plane in which they are secured, then bending the mat into circular form and so laterally bending and fanning out the panels as to form a tapered shell, and securing 30 the ends of the panels between inner and outer hoops so as to maintain the form of the tapered annular shell.

2. The method of making a receptacle which comprises securing a series of panels 35 onto a band in substantially parallel relation leaving portions of the panels susceptible to displacement out of the plane in which other portions are secured, then winding the series of panels on a tapered form and thereby 40 distorting the panels relatively so as to form a tapered shell, and securing the ends of the panels between inner and outer hoops.

3. The method of making a receptacle which comprises securing the corresponding 45 ends of a series of panels to a band leaving portions of the panels susceptible to displacement out of the plane in which other portions are secured, then winding the series of panels on a tapered form and thereby laterally 50 distorting and so fanning out the free ends of the panels so as to form a tapered shell, and securing the ends of the panels at the larger end of the tapered shell between inner and outer hoops and securing the ends 55 of the panels and the band at the smaller end of the tapered shell around a bottom.

4. The method of making a receptacle which comprises the preparation of a blank 60 consisting of substantially parallel panels, secured together at one longitudinal edge of the blank and having other portions unconnected and movable out of the plane of the blank and applying it to a stapling mechanism for supporting and advancing the

panels in such a manner that the panels are adjusted to form a tapered annular shell.

5. The method of making a receptacle which comprises assembling a series of panels on a band with corresponding end portions of the panels secured to the band and other panel portions unconnected and movable out of the plane of the series of panels, then applying the assembled structure on a tapered form so that the band is at the smaller end thereof and the panels are fanned out around the form to conform to the taper thereof, and then securing the fanned out panels between inner and outer hoops.

6. The method of making a basket which comprises holding the corresponding ends of a series of panels in substantially a relatively non-separable manner on a straight band so that the remote ends are relatively adjustable transversely to the holding tension at the band end, then applying the series of panels on a tapered form and relatively adjusting the said remote ends to fit around the larger end of the form, and then securing bands to the panels in the adjusted position.

7. The method of making a basket which comprises holding the corresponding ends of a series of overlapping panels in a substantially fixed relative position on a straight hoop strip so that the ends of the panels remote from the hoop strip are relatively adjustable transversely to the holding tension at the hoop strip ends, then relatively adjusting the said remote ends of the panels to fit around a hoop and thereby form the larger end of an annular tapered shell, and then securing the said remote ends of the panels to the hoop.

8. The method of making a receptacle, which comprises assembling a series of panels in parallel relation to form a mat with the panels connected together along one longitudinal edge of the mat, bending the mat into a tapered cylindrical shell with the panels extending longitudinally of the shell, and securing the panels to maintain the form of the tapered shell.

9. The method of making a receptacle which comprises assembling a series of panels in parallel relation to form a mat with the panels connected together along one longitudinal edge of the mat, bending the connected edge portion of the mat around the peripheral edge of a bottom member and the unconnected edge of the mat around a form member of greater diameter than that of the bottom member, and thereby laterally distorting and fanning out the panels into a tapered cylindrical shell, and stapling the connected ends of the panels to the bottom member and the fanned out ends of the panels to a hoop to maintain the form of the tapered shell.

10. The method of making a receptacle which comprises assembling a series of panels

in parallel relation to form a mat with the panels connected together along one longitudinal edge of the mat, bending the mat around a tapered form to form a tapered 5 cylindrical shell with the panels extending longitudinally of the shell, and securing each end portion of the shell between hoops.

11. That step in the formation of a basket which consists in securing a plurality of 10 staves at one end only to a hoop forming strip leaving their other ends free to adapt them to be displaced transversely to vary the diameter of one end with reference to the other end of the basket to be formed.
